UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

COMBINATION COAL AND GAS RANGE.

1,154,038.

Specification of Letters Patent. Patented Sept. 21, 1915.

Application filed August 28, 1914. Serial No. 859,022.

To all whom it may concern:

Be it known that I, HENRY C. MAUL, a citizen of the United States of America, residing at Detroit, in the county of Wayne and State of Michigan, have invented certain new and useful Improvements in Combination Coal and Gas Ranges, of which the following is a specification, reference being had therein to the accompanying drawings.

10 This invention relates to a combination coal and gas range and particularly to that class of stove in which the same oven is heated by means of products of combustion of gaseous fuel or by means of the radiated or conducted heat derived from the combustion of coal or other solid fuel.

In ranges of this class heretofore used, it has been found that the construction of the oven and the arrangement of flues, dampers 20 and burners is not conducive to best results. Therefore I have devised a stove which possesses among its salient features the following:—First, a range that permits of a change of fuel without changing the range, and 25 that has an oven that can be heated by a coal fire, natural or artificial gas, or both gas and coal. Second, a draft equalizing damper in the smoke flue of the coal range or stove to prevent variations in the chimney 30 draft from effecting the operation of the range oven when gaseous fuel is utilized. Third, a flue box that is employed when natural gas is used as a fuel, the flue box co-operating with solid grids in preventing poisonous gas fumes from escaping into a room. 35 Fourth, an opening in the bottom of an oven to admit gas and air to an oven burner with its side walls tapered outward and exposed to serve functionally as a radiator when the 40 burner is removed and the bottom of the opening is closed with a stopper.

The above are a few of the novel features and in the general make up of the stove or range, the parts are constructed with a view 45 of reducing the cost of manufacture and at the same time retain the features by which durability, simplicity, and the ease and accuracy of assembling are secured, and with such ends in view, my invention consists in 50 the novel construction, combination and arrangement of parts to be hereinafter specifically described: the specification being directed more particularly to the preferred

form of construction illustrated by the drawings, wherein—

Figure 1 is a plan of a combination coal and gas range with the grids of the gas range removed; Fig. 2 is a rear elevation of the combination coal and gas range; Fig. 3 is a front elevation of the same, partly broken away and partly in longitudinal section; Fig. 4 is a cross sectional view taken on the line V—V of Fig. 1; and Fig. 5 is a similar view taken on the line VI—VI of Fig. 3 with the burner removed and a stopper or 65 guard in position.

In a combination coal and gas range which embodies the leading characteristics of my invention, there is present a complete solid fuel burning unit which is generally 70 designated by the reference numeral 1 and occupies one end of the stove structure. This coal burning unit has a wall 2 forming an end wall of a substantially rectangular oven located within the stove casing and 75 comprising a bottom wall 3, an end wall 4, a rear wall 5 and a top wall 6. The bottom wall 3 is spaced from the bottom 7 of the stove casing to provide a horizontal flue 8. The bottom 7 of the casing has a tube 9 80 extending into the flue 8 and serving as an air inlet. Connecting with the tube 9 is a depending frusto conical hollow tube 10, connected to the bottom wall 3 of the oven and communicating with the tube 9 to admit 85 air to the burner as is essential when gaseous fuel is used as a heating medium for the oven.

The end wall 4 of the oven is in proximity to the end wall 11 of the stove casing 90 and co-operates therewith in providing a vertical end flue 12, said flue having the lower end thereof in communication with the horizontal flue 8.

The top wall 6 of the oven is spaced from 95 the grids or top 16 of the stove casing to provide a top horizontal flue 17 in communication with the fire box of the coal burning unit 1. The walls 2, 3, 4 and 6 of the oven adjoin the front wall 18 of the stove casing 100 and said front wall has a hinged door 19 whereby easy access can be had to the interior of the oven. The rear wall 14 of the casing and the offset portion 13 of said wall has chimney flues 20 and 21 in communication 105 with a chimney or exhaust pipe 22.

The flue 21 communicates with the rear end of the horizontal flue 8 as best shown in Fig. 5, and a partition 23 has an opening 24 adapted to be closed by a damper 25 in the form of a pivoted shutter that is opened backward into the flue 20 and is closed through the medium of a crank shaft 26 in the top wall 16 of the stove casing contiguous to the chimney 22. The crank shaft 26 10 constitutes a conventional means of opening and closing the damper from the exterior of the stove casing, and when the damper 25 is closed, as shown in Fig. 5, there is a complete coal burning stove or range in 15 which the products of combustion circulate around the oven, pass into the flues 21 and 20 and escape through the chimney pipe 22.

During the use of solid fuel, a closure 27 is placed in the conical tube 10 of the oven 20 flush with the bottom thereof whereby air cannot enter the oven but on account of the flaring walls of the tube 10 the heat from the flue 8 is radiated into the oven so as to counteract the coldness of the unheated 25 cover 27.

Reference will now be had to the gas range portion of the stove and by referring to Figs. 3 and 5, it will be observed that the walls 4 and 5 of the oven have the upper 30 edges thereof cut away whereby the wall 4 is of less height than the remaining walls of the oven, and the wall 5, adjacent the wall 4, of such a height as to accommodate a lowered or depressed end 28 of the top wall 6 35 of the oven.

The top 16 of the stove casing extends beyond the end of the stove proper and is provided with a rectangular opening 29 having the edges thereof flanged, as at 30, to 40 provide a seat for grids (not shown). The opening 29 extends over an end of the oven and the top wall 16 of the casing, at the inner end of the opening 29, is connected by a compound curved housing wall 31 to 45 the upper edge of the casing wall 11. The housing wall 31 therefore co-operates with the lowered or depressed end 28 of the top wall 6 of the oven in providing a flue 32 establishing communication between the 50 upper end of the flue 12 and top horizontal flue 17. The housing wall 31, is an important adjunct as it co-operates with a burner housing 33 in providing a large compartment at an end of the stove for gas 55 burners 34. The housing 33 is horizontally disposed and has the bottom thereof open, as at 35 and supported by brackets 36 and 37 the former being secured to the casing wall 11 in proximity to the rear end thereof, 60 and the latter in the form of a front plate which is suitably secured to the front edge of the casing wall 11 to co-operate with the front wall 18 of the casing in presenting a well designed and neat stove front.

65 The housing wall 31, intermediate the

ends thereof, is formed with a raised center 39 for the two fold purpose, first, of giving more room for the passage of smoke from the flue 17; also containing a trap door 40 permitting access to the flue 12 for 70 cleaning, and secondly forming pockets 38 for burners. The wall 31, in which the pockets are formed, is provided with protuberances or shoulders 41 co-operating with shoulders 42 of the end wall of the housing 75 33 in supporting longitudinally disposed burner holders 43. These holders are provided with openings for depending positioning pins 44 carried by the burners 34 and in addition to these positioning pins said 80 burners have depending pins or feet 45 resting upon the holders 43. The pins 45 co-operate with the holders 43 in supporting the burners in an elevated position within the housing 33, thereby providing sufficient 85 clearance for the admission of air to the housing to insure a perfect combustion or uniform operation of the burners. The gas burners are of the ordinary and well known design for artificial or natural gas and said 90 burners are conveniently disposed to serve grids or openings of the housing 33. The front wall and other walls of the housing 33 is closed to the admission of air. Valve nozzles 48 admitting gas from a header 49 95 to the burners 34 pass through the front wall and project inside. The burners are provided with air mixers 47 and with an opening to fit over the nozzles thereby supporting that end of the burners. A dust 100 pan 80 rests over the opening 35 in the bottom of the housing 33 but is raised from the bottom to admit air flowing around said pan which supplies the mixers 47 and the burners 34. These valves and headers are 105 of the ordinary and well known type and are supported by brackets 50 connected to the top wall 16 of the stove casing. One end of the header 49 is connected to a gas supply pipe 51 that extends rearwardly at the side of the housing 33, and downwardly under the housing in parallelism with the casing wall 11 of the stove for a purpose that will 110 presently appear.

The bottom of the housing 33, at the rear end thereof, has an inclined portion 52 and the rear wall of the housing has an opening 53 throughout its length. Suitably secured to the inclined portion 52 of the housing is a flue box 54 in communication with the housing through the medium of the open rear end thereof. The flue box 54 is fitted under the top wall 16 of the stove casing and extends in proximity to the chimney flue 20, as best shown in Fig. 2. The chimney flue 20 has an opening in communication with the end of the flue box 54 through the medium of a conduit member 55, said member being secured to the outer 120 side of the chimney flue 20 and overlapping 125 130

the open end of the flue box 54, as best shown in Figs. 1 and 2. The conduit member 55 provides a smoke flue from the flue box 54 to the chimney flue and in the open end of the flue box is an equalizing damper 56 which opens into the flue 20 to a horizontal position. The damper 56 is in the form of a shutter having a rock shaft 57 journaled in the bottom 10 of the flue box, and the outer end of said rock shaft has a crank 58 connected to an actuating member 59. The member 59 extends through the top wall or plate 16 of the stove casing in proximity to the chimney 22 and the crank shaft 26 of the damper 23. At the upper end of the member 59 is a handle 60 in the form of a plate or cross head upon which there is embossed or otherwise marked directions as to the use of the equalizing damper. For instance, "Up Gas—Down Coal" thereby indicating that when the member 59 is raised the equalizing damper 56 is open to permit of gas being used in connection with the stove, and that when the member 59 is lowered the equalizing damper 56 is closed to permit of coal being used as a heating or cooking agent of the stove.

Referring now to the use of artificial or natural gas in connection with the oven of the stove structure, see Figs. 3 and 5. Extending into the hollow tube 9 is a burner pipe 61 arranged along the bottom of the stove structure and connected to the gas supply pipe 51 by an air mixer 62, a valve 63 and a T connection 64. The end of the burner pipe 61, within the support 9, is provided with diametrically opposed lugs 65 engaging sockets 66 provided therefor in the top 40 of the support 9. The pipe 61 terminates below the bottom wall 3 of the oven and detachably mounted upon the end of said pipe is the socket member 67 of a gas burner 68. The gas burner 68 is horizontally disposed above the bottom wall 3 of the oven, and this is an essential feature since the elevation of the gas burner permits of sufficient air entering through the tube to insure perfect combustion. As a matter of fact, it 50 has been determined by experiment and actual use of the stove that with the gas burner flush in the bottom of the oven or below the bottom that there is an imperfect combustion and poor baking.

With the tube 9 and the hollow cone-shaped tube 10 a sufficient quantity of air can reach the burner and the products of combustion are deflected or disseminated through the oven by a false bottom or 60 spreader member 69 arranged upon the bottom 3 of the oven. The products of combustion eventually escape through openings 70 provided therefor in the rear wall 5 of the oven into the exit flue 20.

To use coal or other solid fuel in connec-

tion with this stove, the gas burner 68 is removed from the oven and the closure 27 placed in position. The equalizing damper 56 is closed. The products of combustion or heat units can then pass over, around and under the oven similar to an ordinary coal stove, this being accomplished through the medium of the various flues surrounding the oven. But the cover 27 is not heated and would cause a cold spot were it not for the outward sloping walls of the tube 10 which radiate heat so as to bake articles placed over the cover 27. To use gas in connection with the oven, the closure 27 is removed and the gas burner 68 and spreader 69 placed in position as shown in Fig. 3. The equalizing damper 56 is opened and the products of combustion or heated air escape through the openings 70 into the flue 20. When the burners 34 are used in connection with artificial gas, for instance for boiling, the products of combustion rise into the room through the open grids on which a kettle sets. When using natural gas the grids are replaced by a solid top because of an offensive odor, and the products of combustion will be carried off by the flue box through the chimney or exhaust pipe, it being understood that the equalizing damper is open to permit the passage of the products of combustion and that it is only when coal is used that the equalizing damper is closed to give the full chimney draft to the coal burning unit. The equalizing damper prevents variations in the chimney draft from effecting the operation of the range oven with gas. In using either kind of gas in a range having an oven, a gas burner therein, a walled opening for air through the horizontal bottom flue of the oven and exhaust openings from the oven into the chimney flue, any variations in the pull of the chimney or a down draft therein, will derange the baking of the oven. A gas range oven when not connected to a chimney is constructed to work perfectly, but when connected to a chimney the variations therein will very often spoil baking whether the chimney has too strong a draft and pulls the heat out of the oven too rapidly, or whether it has a back draft and smother the burner. These irregularities are taken care of by the equalizing damper, which when open admits air from the room into the chimney flue if the draft is too strong, and if the back draft occurs the downward current finds a vent through the equalizing damper into the room and does not allow the back draft to interfere with the oven.

The levity of the products of combustion in the oven causes a steady flow of fresh air to the burner through the tube 9 and the conical tube 10 into the oven and through the openings 70 into chimney flues 20.

* It is thought that the operation and utility

of the combined coal and gas range will be apparent without further description, and while in the drawings there is illustrated a preferred embodiment of the invention, it is 5 to be understood that the structural elements are susceptible to such changes, as in the size, shape and manner of assemblage as fall within the scope of the appended claims.

What I claim is:—

10. 1. In a combination coal and gas range, an oven surrounded on the top, end and bottom by smoke flues for coal, a walled opening through the bottom smoke flue for the entrance of external air, a gas supply 15 pipe in such opening, a gas burner removable from said supply pipe, said burner being of a larger diameter than said opening and located above the bottom plate of said oven, leaving a free air space between said 20 burner and said oven bottom.
2. In a combination coal and gas range, an oven surrounded on the top, end and bottom with smoke flues for coal, a smoke flue on the back of said oven connected to the 25 bottom smoke flue and a smoke exit in the top of said range, the oven having an opening through the back wall in said back smoke flue, a chamber, containing gas 30 burners, located over said smoke flue above the oven, and open to the air of the room, a direct damper opening from the smoke flue above said oven into the smoke flue back of the oven, an equalizing damper under the stove top connecting said smoke 35 flue with said burner chamber and thence with the air of the room, a walled opening through the bottom smoke flue, and an oven gas burner located above the oven bottom.
3. A combined coal and gas range com-

prising a stove structure, an oven having a 40 hollow tapering opening through its bottom, a closure supported within the conical opening below the level of the oven bottom allowing radiated heat from the conical sides of the opening to be radiated into the oven. 45

4. In a combination coal and gas range having top and end smoke flues, a burner chamber under the stove top and having a wall over the top and end smoke flues, said wall having concave end portions restricting 50 the top flues and a convex portion intermediate the concave portions of said wall and provided with an opening, a door normally closing said opening, said convex portion of said wall increasing the cross sectional area 55 of said top flue to compensate for the restricted portions of said flue, whereby said top flue has the conduit capacity of said end flue, and a burner above each concave portion of said wall. 60

5. In a combination coal and gas range, a substantially rectangular oven having top and end flues with the top of said oven depressed between said top and end flues, a burner chamber under the stove top and having a wall in parallelism with the depressed portion of said oven top, said chamber wall having a convex intermediate portion provided with an opening, a door normally closing said opening, and a burner 70 above said chamber wall at each side of the convex portion thereof. 65

In testimony whereof I affix my signature in presence of two witnesses.

HENRY C. MAUL.
